UNITED STATES PATENT OFFICE.

MAX RICHTSTEIG, OF CINCINNATI, OHIO.

DESIGN FOR A CASING FOR A SOUND-PRODUCING INSTRUMENT.

55,645.

Specification for Design.

Patented July 6, 1920.

Application filed March 25, 1920. Serial No. 368,755. Term of patent 14 years.

To all whom it may concern:

Be it known that I, MAX RICHTSTEIG, a citizen of the United States, residing at Cincinnati, in the county of Hamilton and State of Ohio, have invented a new, original, and ornamental Design for a Casing for Sound-Producing Instruments, of which the following is a specification, reference being had to the accompanying drawing, forming part thereof.

Figure 1 is a perspective view, showing the lid at the rear partly raised; Fig. 2 is a front elevation, showing the lid at the rear partly raised.

I claim:

The ornamental design for a casing for a sound-producing instrument, as shown.

MAX RICHTSTEIG.
